UNITED STATES PATENT OFFICE.

HENRY C. BUNTING, OF DUNBAR, PENNSYLVANIA.

HINGE-SEAT GAGE.

No. 899,947.

Specification of Letters Patent. Patented Sept. 29, 1908.

Application filed July 20, 1907. Serial No. 384,702.

To all whom it may concern:

Be it known that I, HENRY C. BUNTING, a citizen of the United States, residing at Dunbar, in the county of Fayette and State of Pennsylvania, have invented new and useful Improvements in Hinge-Seat Gages, of which the following is a specification.

This invention relates to hinge seat gages of the type employed in the operation of forming hinge receiving mortises, and has for its objects to provide a comparatively simple, inexpensive device of this character adapted for measuring the length, breadth and depth of the mortise to be formed, and one wherein the parts of the gage may be conveniently adjusted to accord with mortises of varying dimensions.

With these and other objects in view, the invention comprises the novel features of construction and combination of parts more fully hereinafter described.

In the accompanying drawings: Figure 1 is a perspective view of a gage embodying the invention. Fig. 2 is a bottom plan view 25 of the same. Figs. 3 and 4 are detail, sectional views taken respectively on the lines 3—3 and 4—4 of Fig. 1. Fig. 5 is a detail view of one of the clamping screws.

Referring to the drawings, it will be seen 30 that the gage embodies an elongated base member or plate in which is formed a transversely extending groove or channel 3 and a longitudinally extending slot 4 of a length equaling substantially one-half the length 35 of the plate and arranged at a point remote from the channel 3, while inscribed on the upper face of the plate at one side of the slot 4 is a graduated scale 5 denoting inches and fractions thereof.

Projecting from the base plate 1 is a pair 40 of relatively spaced end gage members or arms 6 and 7, of which the former is provided at its inner end with a foot 8 slidably arranged in the channel 3 and to extend 45 transversely of the base plate, while the arm 7 is in like manner provided at its inner end with a foot 9 extended transversely of and arranged to bear on the upper face of the plate, at the lower face there is disposed in line with the foot 9 a bearing piece 10 having 50 a slot 11 through which a clamping screw 12 is entered for engagement with the arm 7. The base plate 1 is provided with a transverse slot 13 disposed centrally of the

channel 3 to receive a clamping screw 14 engaged with the inner end of arm 6. 55

Adjustably mounted on the arms 6 and 7 is a side gage member or bar 15 extended longitudinally in parallel relation with the plate and having at one end an opening 16 adapted to accommodate the arm 6, there being provided in the bar at a point remote from the opening 16 a pair of longitudinally extending slots 17 and 18 formed transversely through the bar at right angles to each other and of which the slot 17 receives the arm 7 and serves with the slot 4 for permitting adjustment of the said arm toward and from the arm 6. The arms are provided with longitudinal slots 19 which provide for adjustment of the bar 15 toward and from the base plate and accommodate respectively clamping screws 20 and 21 extended transversely through the arms and bar and equipped with adjustable clamping 70 nuts 22, there being formed on the screw 21, which during movement of the arm 7 travels back and forth in the slot 18, an elongated head 23 formed to fit in the slot 18 for fixing the screw against rotation. 80

In practice, the arm 7 may, by loosening the screw 12 and nut 22, be moved toward or from the arm 6 to accord with the length of the hinge leaf, while the bar 15 may, by loosening the nuts 22, be moved back or forth toward the base plate 1 to accord with the width of the hinge leaf, after which the clamping screws are tightened for fixing the parts in adjusted position. 85

In using the gage, it is laid flat on the door or door frame to be mortised and lines drawn at the inner edges of the arms 6 and 7 and bar 15 to show the length and breadth of the mortise, the depth of which will correspond with the distances between the bases of the arms and the front edge of the plate 1 which accords with the standard thickness of the hinge leaves. 90

Having thus described my invention, what I claim is:

1. A gage of the class described comprising a base plate having a longitudinally-extending slot at one end and a transversely-extending slot at the opposite end, a pair of arms projecting perpendicularly from the top of the plate and each provided with a longitudinally-extending slot, clamping means for the arms and including screws passing 105

- through the slots of the base plate for transverse adjustment of one arm and transverse and longitudinal adjustment of the other arm, a gage bar slotted at its ends for receiving the slotted extremities of the arms, and clamping devices including screws passing through the slots of the gage bar and arms for adjustably securing the gage bar in position.
2. A gage of the type described comprising a base plate, a pair of gage arms projecting perpendicularly from the plate and provided at their inner ends with cross heads extended transversely of the plate, said arms being adjustable in a direction transversely of the plate for projecting the cross heads beyond one edge of the latter, and one of the arms being movable longitudinally of the plate toward and from the other, means for fixing the arms in adjusted position, a gage bar adjustably mounted on the arms

for movement toward and from the base plate, and means for fixing the bar in adjusted positions.

3. A gage of the class described comprising a base plate, an arm secured thereto for lateral adjustment, a second arm, means for securing the second arm to the base plate and providing for adjustment of the arm both longitudinally of and transversely to the base plate, a gage bar, means for connecting the bar with the first-mentioned arm for adjustment toward or away from the base plate, and means connecting the bar with the second arm to permit of relative adjustment.

In testimony whereof, I affix my signature in presence of two witnesses.

HENRY C. BUNTING.
